UNITED STATES PATENT OFFICE.

JAMES K. MCINTYRE, OF EASTON, PENNSYLVANIA, ASSIGNOR TO INGERSOLL-RAND COMPANY, OF JERSEY CITY, NEW JERSEY, A CORPORATION OF NEW JERSEY.

CENTRIFUGAL PUMP.

Application filed September 23, 1926. Serial No. 137,297.

This invention relates to centrifugal pumps and more particularly to pumps for liquids, operating at extremely low suction pressures.

5 The invention has for its object to increase the efficiency of a two stage centrifugal pump in which the suction pressure is extremely low, to provide a relatively compact arrangement of inlets and outlets for 10 the various stages and furthermore to balance the end thrusts of the various stages effectively.

15 The invention will be more completely understood by reference to the following description of an embodiment of the invention shown in the drawing.

In the drawing a centrifugal pump embodying the invention is shown in longitudinal vertical section.

20 Referring to the drawing, the outer casing of the pump is shown in two parts, the lower part A being provided with a base B and bearing supports C for the drive shaft D. The end bearings E may be of any suitable 25 description. The upper part F of the casing is adapted to be attached in any suitable manner to the lower part A and the two parts A and F together form stuffing boxes G which, with suitable packing material H 30 and glands K prevent the escape of liquid from the casing.

The pump in this instance is of the two stage type, there being provided a first stage wheel L and a second or high pressure stage 35 wheel O both driven and supported by the single shaft D. The pump is designed to operate at a high vacuum in the suction pipe. For this reason the first stage wheel L is provided with large inlets P in order that 40 the velocity set up be relatively low. Furthermore, the outlet openings Q from the first stage wheel L are relatively large and the diameter of the wheel is relatively small in order that the peripheral, relative and absolute velocities be kept low. In this stage 45 the pump is designed to bring the discharge pressure up to, at least, the atmospheric pressure.

The second wheel or impeller O is provided with a relatively small inlet R and discharge openings S in the usual manner. Since there is a slight positive pressure on its inlet the impeller can be designed for its maximum efficiency. As above described 50 the two impellers L and O differ radically

in their construction. The first provides large inlets and low velocities drawing the water at a high vacuum, and the second impeller provides relatively small inlets and operates with a slight pressure at its inlet. 60 Since approximately one third of the work is done in the first impeller of the two stage pump and since its efficiency is somewhat low on account of the necessity of providing over-size openings and further since approximately 65 two thirds of the work is done in the second or high efficiency impeller, the overall efficiency of the unit is increased over that which is to be expected from a pump having two similar impellers. 70

The inlet T for the first stage is located in the casing between the two impellers L and O. The passage U leading to the impeller inlets P is formed by webs V cast integrally with the upper and lower parts F and A 75 respectively of the casing, which also serves as a partition forming part of the discharge passage leading to the second stage impeller O. The inlet and discharge passages, therefore, intertwine into a compact arrangement 80 which can very conveniently be situated between the two impellers L and O. The second stage impeller is surrounded by a passage W leading to a discharge opening X for connection with a suitable delivery pipe. 85

The shaft D may be provided with a suitable flange Y for connection with a convenient source of power for rotating the impellers L and O.

It will be noted that since the outer end 90 faces of the impellers L and O are opposed to each other, and since the pressure on the back of the high pressure impeller O is approximately twice the pressure on the back of the low pressure impeller L and further 95 since the unbalanced area of the high pressure impeller O is approximately one-half the unbalanced area of the low pressure impeller L, the tendency toward axial thrust in the individual impellers acts in opposite 100 directions and hence are neutralized.

I claim:

1. A two stage centrifugal pump comprising a casing, a pair of impellers having inlets opposed to each other, the first stage impeller inlets being larger than the second stage impeller inlets and the first stage impeller being of less diameter than the second stage impeller. 105
2. A two stage centrifugal pump comprising 110

ing a pair of impellers having their inlets opposed to each other, a casing forming inlet and discharge passages for the first stage impeller intertwined between the two impellers, the first stage impeller being provided with relatively large inlet openings directed axially and arranged to operate at low fluid velocities and somewhat low efficiency and said second stage impeller being provided with relatively small inlet openings and arranged to operate at high fluid velocity and high efficiency, the two efficiencies

combining in such a manner as to produce a high overall efficiency and a single shaft for driving and supporting said impellers. 15

3. A two stage centrifugal pump having a pair of impellers with opposed inlets, the first stage impeller being of lesser diameter and having a greater unbalanced area than the second stage impeller to neutralize the 20 axial thrust of the individual impellers.

In testimony whereof I have signed this specification.

JAMES K. McINTYRE.
